ANTENNA TUNING CIRCUIT

Dudley E. Foster, South Orange, N. J., assignor to
 Radio Corporation of America, a corporation of
 Delaware

Application December 16, 1937, Serial No. 180,106

4 Claims. (Cl. 250—20)

My present invention relates to signal receiving systems, and more particularly to a radio receiving system utilizing a tunable signal collector.

It is well known that a high signal to noise ratio at the signal collector of a radio receiving system is beneficial. For this reason radio receivers, particularly those adapted to receive signals in the broadcast range, are provided with signal collector circuits of high gain. For example, a high gain signal collector, or antenna circuit, usually employs an inductance element of large magnitude. However, as the receiving system employed with such a high gain signal collector is varied in frequency through the tuning range, the collector gain decreases by virtue of the fact that the collector is naturally resonant to a given frequency of the receiver tuning range. While it would be feasible to provide a variable capacity to tune the signal collector over the operating signal range of the receiver, the variable capacity being ganged with the receiver tuning control condensers, yet such a device would not be practical because a variable capacity cannot be used in a practical manner to tune the signal collector circuit. On the other hand, it is equally undesirable to employ a variable inductor in the antenna circuit, since it would be necessary to gang the latter with the variable tuning condensers of the receiver.

Accordingly, it may be stated that it is one of the main objects of my present invention to provide a signal collector circuit for a tunable radio receiver, wherein the collector circuit is constructed to have a high gain, and an electronic device being electrically associated with the signal collector circuit so that the latter may be conjointly tuned with the receiver over the tuning range thereby to preserve a high signal to noise ratio at the collector circuit.

Another important object of my invention may be stated to reside in the provision of a radio receiver provided with a tuning instrumentality, and the receiver being equipped with a signal collector circuit having a high inductance value thereby to provide a high signal to noise ratio at the low frequency end of the receiver tuning range, and means being employed to tune the collector circuit conjointly with the receiver over the tuning range, and without physically changing the inductance in the collector circuit, thereby to preserve said ratio over the tuning range.

Another object of my invention may be stated to provide a signal collector circuit adapted to be used, in general, for radio receivers which are

tunable over a wide range of signal frequency, the collector circuit being of the type having a reactive element of high inductive magnitude thereby to provide a high signal gain at the low frequency end of the said signal range, and an electronic device being electrically associated with the collector circuit reactive element so that the electronic device may be adjusted to vary the inductive magnitude of said reactive element in 10 a sense to adjust the collector circuit frequency over the wide signal range.

Still other objects of my invention are to improve generally the simplicity and efficiency of radio receivers, and more particularly to provide 15 more efficient signal collector circuits for radio receivers, and which collector circuits are not only reliable in operation, but are economically manufactured and assembled in radio receivers.

The novel features which I believe to be characteristic of my invention are set forth in particularity in the appended claims; the invention itself, however, as to both its organization and method of operation will best be understood by reference to the following description taken in 20 connection with the drawing in which I have indicated diagrammatically several circuit organizations whereby my invention may be carried into effect.

In the drawing:

30 Fig. 1 shows a circuit arrangement embodying one form of my invention, and

Fig. 2 illustrates another embodiment of the invention.

Referring now to the accompanying drawing, 35 wherein like reference characters in the two figures designate similar circuit elements, there is shown in Fig. 1 a signal collector circuit of the grounded antenna type. The numeral 1 designates the grounded antenna circuit, and the 40 antenna circuit includes the coil 2. The high alternating potential end of coil 2 is connected, as by signal frequency coupling condenser 3, to the input electrode of the first radio frequency amplifier 4. The amplified radio frequency signals are impressed upon the tunable signal selector circuit 5 which is adapted to be connected to the input electrodes of the following signal transmission tube. The selector circuit 5 includes a variable condenser 6 which is adapted to vary 45 the tuning of selector circuit 5 over a desired signal frequency range. It is to be understood that the numeral 6 denotes the usual tuning device employed for broadcast receivers; that is, receivers operating at a signal range of 550 to 500 kc.

If the receiver is of the superheterodyne type, then the selector circuit 5 may feed into a first detector, or an additional radio frequency amplifier stage; the stages following the first detector are too well known to be recited. The dotted line connected to condenser 6 has been designated as the "Tuner," and it will be understood that this instrumentality is adapted to vary the rotors of a gang of variable condensers usually employed in a broadcast receiver. If the receiver is of the tuned radio frequency amplifier type, then numeral 6 represents the gang of variable condensers employed in the cascaded signal selector circuits. The magnitude of coil 2 should be chosen so that it resonates with the inherent capacity of antenna 1 to a frequency at the low frequency end of the receiver tuning range, the tube 7 being biased to cut-off. For example, in the broadcast band of 550 to 1500 kc., the antenna circuit including coil 2 will be series resonant to a frequency of 550 kc.

As the tuning device of the receiver is varied toward the high frequency end of the tuning range, it is necessary to adjust the tuning of the signal collector in synchronism with the receiver tuning device. As stated before, it is not practical to do this by utilizing a variable capacity in the antenna circuit; and it is not desirable to physically vary the coil 2. According to my invention, however, the collector circuit is varied in frequency by the relatively simple and efficient device shown in Fig. 1. There is utilized an electron discharge tube 7, say of the pentode type, which has a cathode 8, a control grid 9 and a plate 10. The usual positive screen grid and a suppressor grid are employed between the plate 10 and control grid 9. The control grid 9 is connected to the junction of resistor 11 and condenser 12, the latter elements being connected in series across the coil 2. The connection between control grid 9 and the junction of resistor 11 and condenser 12 is made through a condenser 13 which has a low impedance to currents of signal frequency. The cathode 8 is connected to ground through a resistor-condenser network 14 which functions to provide a fixed bias for the control grid 9. It is desirable to choose the bias such as normally to cut off the flow of plate current in tube 7, when the tuning device of the receiver is adjusted to the low frequency end of the tuning range.

The plate 10 is connected to a source of proper positive potential, as the power supply bleeder resistor of the receiving system, through a coil 15. The plate 10 is, also, connected to the high potential end of coil 2 through a condenser 16. There is provided an adjustable potentiometer for varying the bias of the control grid 9, and the potentiometer comprises a bleeder resistor 17 having an intermediate point thereon at ground potential. An adjustable tap 18 is arranged to slide along the resistor 17 between the grounded point thereon and the positive potential terminal thereof. The control grid 9 is connected to the tap 18 through a connection including resistor 19.

Of course, the bleeder resistor 17 may be a portion of the common potential supply circuit of the receiving system. The broken line 20 denotes a mechanical coupling between the adjustable tap 18 and the tuning device of the receiving system. This mechanical coupling 20 may be of any desired construction, it being only necessary to point out that the coupling should be such that as the rotors of the gang of varia-

ble condensers are adjusted to tune the receiver selector circuits from the low frequency end of the tuning range toward the high frequency end thereof, then the tap 18 will be adjusted from the grounded point on bleeder resistor 17 toward the positive potential terminal.

When the receiver is tuned to the low frequency end of the tuning range, then it is to be understood the tap 18 will be at the grounded point on the bleeder resistor 17. In that case a plate current cut-off bias will be impressed on the control grid 9 by virtue of the voltage drop across the bias network 14. This means that the tube 7 will be inoperative, and will produce no effect as far as coil 2 is concerned. However, as the tuning device is adjusted to increase the frequency of the receiver selector circuits, the tap 18 will be adjusted in a positive potential sense and, hence, increase the gain of tube 7. An increase in the gain of tube 7 will result in the reduction of the inductive magnitude of coil 2, and the decrease in inductive magnitude of coil 2 will be at a rate such that the antenna circuit frequency will increase in synchronism with the frequency of the receiver selector circuits. This proper and synchronous change in the inductive magnitude of coil 2 is secured by proper adjustment of tap 18 along the bleeder resistor 17.

The tube 7, and its input and output connections to coil 2, functions as a "quadrature" tube. That is, the plate current flowing through coil 2 from tube 7 is in quadrature relation with the voltage across that coil by reason of the voltage impressed on the control grid 9 and derived from the junction of resistor 11 and condenser 12. As the gain of tube 7 increases, the quadrature current increases, and this, in turn, increases the inductive effect of tube 7 which is in shunt across coil 2 thereby decreasing the inductive magnitude of the coil. Condenser 16 and coil 15 can have their magnitudes chosen so that they are series resonant at some frequency producing a large impedance change at that frequency. In the form of circuit shown in Fig. 1, the plate current of tube 7 actually flows through coil 15, but since the latter coil is in shunt relation with coil 2, the increase in quadrature current flow through coil 15 actually results in a decrease in the inductive magnitude of coil 2. When the plate potential for tube 7 is supplied through coil 15, then a signal frequency by-pass condenser 21 is connected between the grounded end of coil 2 and the low potential end of coil 15. The quadrature tube 7 is limited in the inductive effect it can produce. It can act like a high inductive, but it is limited by its mutual conductance to the lower limit of inductance effect it can produce in shunt with a coil.

By adding the condenser 30 in series with coil 2 in the antenna circuit 1, as shown in Fig. 2, it is possible to use a much larger inductance magnitude for coil 2 than in the case of Fig. 1. Hence, a greater variation of signal collector frequency is possible, and the tube 7 may be chosen to have a relatively lower mutual conductance than in the case of the circuit shown in Fig. 1. The arrangement in Fig. 2 differs from that shown in Fig. 1 in that the plate 10 is connected directly to the junction of condenser 30 and coil 2; the low potential end of coil 2 may be connected to a point B of positive potential. The cathode 8 of the quadrature tube 7 may be connected to ground, and instead of using a special self-biasing network 14, the tap 18 may be

adjusted to the negative side of the bleeder resistor 17 and to a point thereon such that cut-off bias is applied to control grid 9. In other words, by sliding tap 18 from the negative section of bleeder resistor 17 toward the positive section thereof, the gain of tube 7 may be controlled. The operation of the circuit shown in Fig. 2 is similar to that of Fig. 1. There is impressed on the control grid 9 a signal potential which is in quadrature relation with the plate current flowing from tube 7 through coil 2.

Let us consider Fig. 2, and assume that condenser 30 is so large that it exercises no tuning function; say it has a value of 0.01 mmf. Let us further assume that tube 7 has a maximum mutual conductance of 1500 micromhos. With tube 7 cut off, coil 2 should be resonant with the capacity of antenna 1 to the lowest desired tuned frequency; say 550 kc. Assuming that the antenna has a typical value of capacity of 150 mmf., coil 2 must have an inductance value of 560 mh. The radio frequency resistance of such a coil is usually of the order of 10 ohms at 550 kc., and increases approximately proportional to frequency. The antenna resistance may likewise be of the order of 10 ohms; in which case the resonant step-up of the antenna circuit will have a value of 75, whereas with ordinary circuits a value of antenna circuit step-up of 20 is considered good. Now, as has been shown in the technical literature, the effective inductance value produced by tube 7 in the connection shown is given by the expression RC/Gm , where R is the value of resistor 11, C is the value of capacity 12, and Gm is the mutual conductance of tube 7.

For maximum tuning range the minimum value of effective inductance produced by tube 7 should be as low as possible, and, as the expression above indicates, this means a low value of R and C and a high value of Gm. However, there is a practical lower limit to the value of R, since the lower R is, the greater will be its effect on the power factor of coil 2 and the less will the gain value circuit. The effect of a given value of R will be greater if coil 2 and antenna 1 have low losses (low resistance) than if they have high resistance. Furthermore, a minimum to the value of C is set in practice by the input capacity of tube 7 and the distributed capacity of the associated circuit wiring. This usually limits the minimum value of C to about 10 mmf. The limit to Gm is set by available tubes, and is usually between 1000 and 2000 micromhos maximum. This means that for a frequency range of tuning of 3 to 1, R would have to be approximately 10,000 ohms, since the minimum value of inductance due to coil 2 and effective inductance of tube 7 in parallel must be about 56 mh. If this value were achieved with Gm of 1500 micromhos, the receiver would tune from 550 to 1750 kc. However, the required value of R to accomplish this we have seen to be 10,000 ohms; but this value results in so unfavorable a power factor for the circuit that the gain would be only 3 or 4, in place of the 75 noted above. It is obvious, therefore, the R cannot be as small as 10,000 ohms, if high gain is to be realized in the antenna stage.

If now, the value of antenna capacity were halved, the value of coil 2 necessary to tune to the lowest desired frequency would be doubled, and the value of equivalent inductance required to be produced by tube 7 to tune to the highest frequency would likewise be doubled, allowing

the use of a larger resistor R (resistor 11). The same result, as far as the circuit is concerned, can be obtained by inserting a capacity 30, as by using a low capacity antenna. For example, if the antenna capacity of 150 mmf. considered previously be employed, and condenser 30 has the value of 50 mmf., the antenna circuit will have a capacity of 37.5 mmf. and coil 2 will have a value of 22.40 mh. Tube 7 will then only be required to produce a minimum of 315 mh. to tune from 550 to 1500 kc. Using the same value of C and Gm as before, R may be 47,000 ohms and obtain this inductance value. The gain obtained with this value of coil 2 and R would be approximately 8. A still further reduction of the size of condenser 30 would permit the use of a larger resistor 11 with consequent higher gain.

If, now, we consider Fig. 1, there are two resonant circuits capable of adjustment, the capacity of antenna 1 and the inductance of coil 2 which will be chosen to resonate at the lowest desired frequency as before, and coil 15 and condenser 16. Coil 15 may be large, say of the order of 5 millihenries, in which case it has been shown that a given minimum value of effective inductance due to tube 7 produces a greater tuning effect than if coil 15 were small. But this high value of inductive reactance due to coil 15 and tube 7 will not usually be sufficiently low to tune to the highest desired frequency, unless condenser 16 be added in series therewith. The reactance of condenser 16 being opposite in sign to that of coil 15 and tube 7, it will cause a lower total net effective reactance across coil 2, and thus cause variations of inductance due to changing the grid bias on tube 7 to produce a greater tuning effect.

While I have indicated and described several systems for carrying my invention into effect, it will be apparent to one skilled in the art that my invention is by no means limited to the particular organizations shown and described, but that many modifications may be made without departing from the scope of my invention, as set forth in the appended claims.

What I claim is:

1. An input system for a radio receiver consisting of an inductance connected between a signal collector and ground, a series combination of a capacity and a second inductance effectively connected in shunt with the first inductance, a tube having its output connected across said second inductance and having its input circuit connected to a quadrature circuit connected across said second inductance, and means for varying the direct current grid bias on the tube whereby the resonant frequency of the said entire input system is caused to vary in response to the variations of the grid bias potential.

2. A receiving system having in combination a selector circuit tunable over a range of signal frequencies, an antenna circuit coupled to the selector circuit and having a high inductance coil which resonates with the inherent capacity of the antenna circuit at the low frequency end of the above range of frequencies, a thermionic impedance effectively in shunt to said antenna circuit coil for controlling the effective impedance of said coil, means for varying said thermionic impedance, and means for adjusting the tuning of the selector circuit conjointly with adjustment of said impedance varying means.

3. A receiving system having in combination a selector circuit tunable over a range of signal

5 frequencies, an antenna circuit coupled to the selector circuit and having a high inductance coil which resonates with the inherent capacity of the antenna circuit at the low frequency end of the above range of frequencies, an electron discharge tube having its space discharge path effectively in shunt to said antenna circuit coil, means for varying the impedance of said discharge path and in consequence the effective impedance of said coil, and means for adjusting the 10

tuning of the selector circuit conjointly with adjustment of said impedance varying means.

4. A receiving system according to claim 3 wherein the impedance varying means comprises the control grid of the electron discharge tube, and the tube is biased to substantially plate current cut-off with adjustment of the selector circuit to the low frequency end of the frequency range.

DUDLEY E. FOSTER.
